UNITED STATES PATENT OFFICE.

LAWRENCE E. ROBINSON, OF COFFEYVILLE, KANSAS.

GAS PACKING-HEAD.

1,114,808.

Specification of Letters Patent.

Patented Oct. 27, 1914.

Application filed December 20, 1913. Serial No. 807,873.

To all whom it may concern:

Be it known that I, LAWRENCE E. ROBINSON, a citizen of the United States, residing at Coffeyville, in the county of Montgomery and State of Kansas, have invented certain new and useful Improvements in Gas Packing-Heads, of which the following is a specification, reference being had therein to the accompanying drawing.

10 This invention relates to certain new and useful improvements in gas packing heads to be used in connection with driving nipples for oil wells; the object being to provide a head which can be adjustably mounted upon the drive pipe so as to overcome the disadvantages now existing in having to cut and thread the pipe in order to mount the head thereon.

Another and further object of the invention is to provide a head which is so constructed that the same is mounted upon the drive pipe and casing in such a manner that a tight joint is obtained between the respective members in order to prevent the 25 gas from escaping around the drive pipe or casing; said head being provided with gas outlets by which suitable pipes can be connected for conveying the gas to the desired point.

30 Another and further object of the invention, is to provide a head which is especially adapted to be used in connection with the telescoping packer when the well is being bored through different strata of earth containing gas and water.

Another and further object of the invention is to provide the head with a neck member detachably mounted thereon in such a manner that the same can be easily and 40 quickly detached in order to substitute a neck member with a bore of a larger or smaller diameter to receive the casing.

Another and still further object of the invention is to provide a segmental frusto-conical gripping ring having serrated faces for engaging the drive pipe or nipple in order to fasten the head in its adjusted position thereon, without cutting the drive pipe, thereby enabling the head to be readily placed in position at the desired height.

Other and further objects and advantages of the invention will be hereinafter set forth and the novel features thereof defined by the appended claims.

55 In the drawings—Figure 1, is a side elevation of my improved construction of gas

packing head; Fig. 2, is a vertical section through my improved construction of head showing the application of the same to the casing and drive pipe in position within an 6 oil well showing a telescoping packer in expanded position upon the casing; Fig. 3, is a top plan view of the head; and Fig. 4, is a section taken on the line 4—4 of Fig. 2.

Like numerals of reference refer to like 65 parts in the several figures of the drawings.

In the drawings, 1 indicates a well casing arranged in position within a well having a telescoping packer 2 adjacent its lower end for closing the well at the desired point between the different strata of gas and water-bearing sand; said packer having a shoe 3 resting upon the shoulder at the bottom of the well as clearly shown.

Surrounding the casing 2 at the upper 75 portion thereof, is an ordinary driving nipple or drive pipe 4 which is placed in position within the well and extends upwardly beyond the surface thereof. The above description is given so that the operation of 80 my construction of head when placed in position upon a drive nipple and casing, can be readily understood.

Slidably mounted upon the upper end of the drive pipe 4 is a depending sleeve portion 5 of the cylindrical head 6 which is provided with suitable gas outlet nipples 7 to which, pipes can be connected for conveying gas to the desired point. Mounted upon the depending sleeve portion 5 of the head 6, is 90 a collar 8 which is provided with a frusto-conical bore portion 9 at its lower end in which is mounted a segmental frusto-conical sleeve 10 formed of a series of sections having serrated inner faces for gripping the 95 drive pipe 4 when the collar is moved upon the sleeve 5 of the head, as will be later described.

Mounted upon the segmental sleeve is a 10 cast iron ring 11 on which is arranged a ring of packing material 12 which is compressed by the lower end of the sleeve portion 5 of the head 6 against the outer face of the casing 4 in order to form a gas-tight joint.

The head 6 is provided with an annular groove 13 in its top in which is seated a lead ring 14 which is engaged by a neck member 15 which is provided with a central bore 16, the upper end thereof being surrounded by an annular recess 17 forming a pocket for a ring of packing material 18

which is compressed therein around the casing 1 by the boss 19 of the cap 20 which is provided with a bore to receive the casing 1.

In order to allow my improved construction of head to be used in connection with various sized casings, I provide neck members 15 with different-sized bores so that by substituting one member for the other with the correct sized bore, casings of various sizes 10 can be used.

For moving the collar 8 in respect to the sleeve portion 5 of the head 6 in order to compress the segments of the ring 10 against the drive pipe 4, I provide the outer face of 15 the collar 8 with oppositely disposed bifurcated lugs 21 which are provided with pockets 22 in their under faces in which are adapted to be seated heads of bolts 23 which extend upwardly parallel with the head and 20 neck member 15 and are provided with nuts 24 engaging the upper faces of the neck member 15 so as to compress the lead ring 14 which forms a gasket in order to prevent the gas from escaping from between the 25 head and neck member.

The cap 20 is provided with an annular upwardly projecting flange 25 and with oppositely disposed slits 26 through which the bolts 23 pass and mounted upon these bolts, 30 are nuts 27 arranged within the annular flange 25 in such a manner that after they have been tightened in order to force the boss 19 against the packing, and to draw the collar 8 upon the sleeve 5 of the head 6 so 35 as to compress the segmental ring, they will be prevented from moving outwardly by the flange 25.

In the drawing, I have shown the drive pipe or nipple 4 arranged within the head 40 at the most desirable point, but it is of course understood that the head can be adjusted vertically upon the end of the drive pipe as the pipe can extend upwardly within the head so as to properly position the 45 head in respect to the surface of the ground upon the drive pipe, without cutting the pipe.

By this construction, after the drive pipe and casing have been placed in position, 50 the head can be quickly adjusted upon the drive pipe and by tightening the nuts 24 and 27, the same will be clamped firmly thereon so as to form a gas-tight joint between the casing and drive pipe.

From the foregoing description, it will be seen that I have provided a gas packing head for oil well casings and drive pipes, 60 which is provided with means for locking the head in its adjusted position upon the drive pipe and means for forming a gas-tight joint around the casing. It will also be seen by the construction set forth in this application, that the compression collar is adjusted upon the head by bolts and nuts 65 performing the double function of com-

pressing the gasket between the interchangeable member and head and the gripping members, the cap being capable of being removed independently of the neck member. It will also be seen that the head is formed 70 hollow and that a clearance is formed therein in order to allow the drive pipe to be extended within the head such a distance that the same can be adjusted so as to accommodate various lengths of drive pipes. 75

I claim:

1. The combination with a drive pipe, of a head slidably mounted thereon provided with a sleeve portion, a collar slidably mounted upon said sleeve portion, gripping members arranged within said collar, packing rings arranged upon said gripping members, and means for adjusting said collar in respect to said head for moving said gripping members into contact with said 85 driving pipe.

2. The combination with a drive pipe and casing, of a head slidably mounted thereon, means for locking said head in adjusted position upon said drive pipe, a neck member 90 and cap member carried by said head surrounding said casing, and a connection between said means and cap.

3. The combination with a drive pipe and a casing, of a head member provided with 95 a sleeve slidably mounted upon said drive pipe, a collar adjustably mounted upon said sleeve portion, gripping members arranged within said collar for engaging said drive pipe, and means for adjusting said collar 100 upon said sleeve and holding the same in adjusted position.

4. The combination with a drive pipe, of a head slidably mounted on said drive pipe, a collar slidably mounted upon said head having 105 a frusto-conical bore portion, a segmental frusto-conical ring arranged within the frusto-conical bore portion of said collar, said segmental ring being provided with serrated gripping faces, packing arranged 110 between the head and said segmental ring, and means for adjusting said collar upon said head for compressing said segmental ring into engagement with said drive pipe.

5. The combination with a drive pipe, of 115 a head slidably mounted upon said pipe, a segmental ring surrounding said drive pipe having an inner gripping face, a collar slidably mounted upon said head, means for adjusting said collar in respect to said head, 120 for compressing said segmental ring against said drive pipe.

6. The combination with a drive pipe and casing arranged concentrically, of a head provided with a sleeve slidably mounted 125 upon said drive pipe, a member mounted upon said head, a gasket arranged between said head and member, a collar slidably mounted upon said sleeve, a clamping member arranged within said collar, and a con- 130

nection between said member and collar for adjusting said collar upon said sleeve.

7. The combination with a drive pipe and casing, of a head slidably mounted upon said drive pipe, means for locking said head in adjusted position thereon, a member arranged upon said head surrounding said casing, a gasket arranged between said member and head, said member being provided 10 with a packing pocket, packing rings arranged within said pocket around said casing, and a cap surrounding said casing having a boss extending into said pocket for compressing said packing.

15 8. The combination with a drive pipe and casing, of a head slidably mounted upon said casing, means for locking said head in its adjusted position thereon, an interchangeable member mounted upon said head, a packing arranged between said interchangeable member and head, said interchangeable member being provided with a packing pocket, a cap member having a boss extending into said pocket upon said packing, and 20 a connection between said cap and head.

9. The combination with an oil well casing and drive pipe, of a head slidably mounted upon said drive pipe, means for clamping said head in adjusted position thereon, a member mounted upon said head surrounding said casing, a cap carried by said member, and packing rings arranged between said members for forming a gas-tight joint between said casing, drive pipe and coöperating members.

10. The combination with a drive pipe, of a head provided with a sleeve portion slidably mounted upon said drive pipe, a segmental frusto-conical ring surrounding said 40 drive pipe, a collar surrounding said segmental ring slidably mounted upon the sleeve of said head, a member mounted upon said head, and a connection between said member and collar for compressing said segmental ring against said drive pipe.

11. The combination with a drive pipe, of a head slidably mounted upon said drive pipe provided with gas outlets, a segmental ring surrounding said drive pipe, a collar 50 slidably mounted upon said head for compressing the segments of said ring against said drive pipe, a member arranged upon said head, a cap arranged upon said member, and bolts connecting said collar to said 55 cap, said bolts carrying nuts engaging the member and cap.

12. The combination with a drive pipe, of a head provided with a sleeve portion slidably mounted upon said drive pipe, a collar 60 slidably mounted upon said sleeve portion provided with a frusto-conical bore, a frusto-conical segmental ring arranged within the frusto-conical bore of said collar, the segments of said ring being provided 65 with serrated gripping faces, bifurcated lugs

formed on the outer wall of said collar provided with seats, bolts provided with heads mounted in said seats, a member mounted upon said head, and nuts carried by said bolts engaging said member for adjusting 70 said collar upon the sleeve of said head.

13. The combination with a drive pipe and casing, of a head slidably mounted upon said drive pipe, a collar mounted upon said head, a segmental gripping ring arranged 75 within said collar, an interchangeable member mounted upon said head, a cap arranged upon said interchangeable member having an annular upwardly projecting flange, said cap being provided with oppositely disposed slits, oppositely disposed lugs formed upon said collar, bolts seated in said lugs extending through the slits of said cap, nuts mounted on said bolts engaging said interchangeable member, and nuts mounted upon 80 said bolts engaging said cap.

14. The combination with a drive pipe or nipple, of a head provided with a sleeve slidably mounted upon said pipe, a member mounted upon said head, a collar slidably 90 mounted upon the sleeve of said head provided with a frusto-conical bore portion, a segmental frusto-conical gripping ring surrounding said drive pipe within said collar, packing rings arranged between said segmental ring and sleeve of said head, packing rings arranged between said head and member, and a connection between said collar and member for adjusting said collar upon said sleeve, compressing said segmental members against said drive pipe.

15. In a gas packing head, the combination with a drive pipe, of a hollow member slidably mounted upon said drive pipe, a member carried by said hollow member having a stuffing box for engaging a well casing, a gripping member carried by said hollow member for engaging said drive pipe, and a connection between said member and gripping member.

16. In a gas packing head, the combination with a drive pipe, of a hollow member mounted upon said pipe, a collar carried by said hollow member, gripping members carried by said collar for engaging said drive pipe when said collar is moved in one direction, and means for adjusting said collar upon said hollow member and locking the same in adjusted position.

17. In a gas packing head, the combination with a drive pipe and casing, of a hollow member slidably mounted thereon, a collar slidably mounted upon said hollow member, gripping members carried by said collar for engaging said drive pipe, superposed members carried by said hollow member surrounding said casing, and a connection between one of said superposed members and collar.

18. In a gas packing head, the combina-

tion with a drive pipe, of a hollow head 5
slidably mounted upon said drive pipe, a
segmental clamping ring surrounding said
drive pipe, a collar surrounding said seg-
mental ring, and means for adjusting said
collar in respect to said head for forcing
said clamping ring into engagement with
said drive pipe.

19. In a gas packing head, the combina- 10
tion with a drive pipe, of a head slidably
mounted upon said drive pipe, clamping
means carried by said head, superposed
members mounted upon said head, and a
connection between said superposed member
15 and clamping means.

20. A gas packing head, comprising a hol-
low member, a collar carried by said hollow
member, a series of gripping members car-
ried by said collar for engaging a drive pipe,

superposed members mounted upon said 20
head member provided with a stuffing box
surrounding a well casing, and a connection
between said collar and one of said super-
posed members.

21. The combination with a drive pipe 25
and casing, of a head member slidably
mounted upon said drive pipe, gripping
means carried by said head member, a cap
mounted upon said head member, and a con-
nection between said gripping means and 30
cap.

In testimony whereof I affix my signature
in presence of two witnesses.

LAWRENCE E. ROBINSON.
